UNITED STATES PATENT OFFICE.

HARLEIGH GILLETTE, OF HIGHLAND PARK, ILLINOIS.

LAMP-BURNER.

SPECIFICATION forming part of Letters Patent No. 373,065, dated November 15, 1887.

Application filed February 10, 1887. Serial No. 237,232. (No model.)

To all whom it may concern:

Be it known that I, HARLEIGH GILLETTE, a citizen of the United States, residing at Highland Park, in the county of Lake and State of Illinois, have invented certain new and useful Improvements in Flat-Tubed Lamp-Burners, of which the following is a specification.

This invention relates to that class of lamp-burners having an automatic extinguishing-plate hinged within a cut-out side of the wick-tube; and it consists of improvements in the form of plate and means for supporting the same, whereby the obstructions due to oil, heat, and refuse are overcome and the extinguisher made to operate practically and continuously, while at the same time the draft of the lighted wick is greatly improved.

Figure 1 is a perspective view of a lamp-wick tube embodying my improved features. Fig. 2 represents the same with the extinguishing-plate removed. Fig. 3 shows the said detached extinguishing-plate, and Figs. 4 and 5 are vertical sections, showing the plate, respectively, in a raised and lowered position.

Referring to the drawings, it will be seen that the wick-tube A has one side, near the top, removed, as shown in Fig. 2, the side edges of the same being extended or turned outward to form the brackets a' a'' . The extinguisher B, consisting of a thick metal plate, is beveled or convexed on the inner side, and has its base b enlarged or bent inward. It is

provided at the angle thus formed with the pivots b' b'' . This extinguishing-plate is arranged within and fills up the cut-out side of the wick-tube, the said pivots b' b'' being journaled out upon the tips of the brackets. The plate proper thus leans at a decided angle with its upper beveled edge against the wick and the enlarged or curved-in base b impinging against the wick-tube below the cut-out portion.

Looking at Figs. 4 and 5, it is apparent that when the wick is lowered beyond a certain point the plate will, by gravity, swing or fall inward and close the mouth of the wick-tube, resting upon the part a in a horizontal position. In this way the flame is instantly and effectually extinguished. In addition, the flame of the lighted wick has its combustion greatly improved by the draft in the direction of the arrows, Figs. 1 and 4.

I claim as my invention—

The combination, in a lamp-burner, of the wick-tube A, having one side near the top cut away and the edges fashioned to form the rest a , and the brackets a' a'' , with the extinguishing-plate B, hinged upon the said brackets and provided with the stop b , all arranged and constructed substantially as and for the purpose set forth.

HARLEIGH GILLETTE.
